UNITED STATES PATENT OFFICE.

VASIL MACKAY, OF WASHINGTON, DISTRICT OF COLUMBIA.

FURNACE.

Application filed June 19, 1920. Serial No. 390,099.

To all whom it may concern:

Be it known that I, VASIL MACKAY, citizen of the United States, residing at Washington, in the District of Columbia, have invented certain new and useful Improvements in Furnaces, of which the following is a specification, reference being had therein to the accompanying drawing.

The present invention relates to stoker 10 grates of the front feeder type and to the extent that the subject matter is common to the two cases, this application is to be regarded as a continuation of my application, Serial No. 336,442, filed November 7, 1919, 15 entitled Mechanical stoking grate support.

In the present case, as also in the application to which I have alluded, the customary dead plate located forwardly of the furnace is obviated, and movable feeding grate members are located to bring the forward edges thereof immediately adjacent to the fuel receiving opening of the fire chamber to better facilitate the feeding of the fuel rearwardly over the grate.

25 In these cases also I have been enabled to eliminate dividing walls in the front plate of the furnace so that a continuous or unbroken fuel feeding opening is furnished across the front of the furnace, thereby permitting a feeding of the fuel to several adjoining stoker grate sections through one and the same opening, the adjoining sections being arranged side by side and preferably inclined directly from the fuel opening 30 downwardly and rearwardly of the fire chamber, and the grate members being actuatable to cooperate with the inclined nature of the grate in shifting the fuel in a gradual and satisfactory manner throughout the 35 length of the fire chamber to a dumping point, provided for clinkers, etc., at the back of the fire chamber.

In my prior, but still copending application, I have disclosed improved supporting 45 means for the grate, and an object of the present invention has been to further perfect said supporting means in a manner lending to the simplicity, better assembling of the parts, improved functioning of said 50 parts permitting expansion and contraction thereof without impediment from rigid or bolted connections as in the earlier instance; and the arrangement of the long fuel feeding opening so that the same is usable in 55 connection with my improved feed hopper set forth in my copending application, filed

August 29, 1919, Serial No. 320,605, without creating obstructing interference with the use of long actuating levers quite desirable to be employed as part of the actuating 60 means for the grate members.

It will be appreciated that where the fuel feeding opening is in length coincident with the width of the assembled adjoining grate sections, as in my first above mentioned 65 application, it is difficult, if not impossible, to afford sufficient space at the front of the furnace and beyond the ends of the feed opening to allow for the provision of long upwardly projecting handles or levers, and 70 such an arrangement prevents the employment of a feed hopper unless some breakdown or sectional arrangement of levers projecting unduly forwardly of the furnace to a point to escape the hopper is utilized. 75

As distinguished from the foregoing, in my present construction, I still secure the advantages of the elongated fuel inlet opening and the use of a hopper feed in conjunction therewith, while at the same time allowing for the use of long grate actuating levers located at the ends of the hopper and normally confined within the space defined by the front wall of the furnace and the outer or front plane of the hopper. 80

The improved features herein outlined as well as others appealing to persons skilled in the art to which the invention relates, will be apparent from the detailed description hereinafter contained when read in connection 85 with the accompanying drawings, forming part hereof, and wherein the preferred embodiment of the invention is illustrated.

In the drawings:

Figure 1 is a perspective view of the improved grate associated with the furnace, the latter being illustrated merely in a fragmentary way to render the disclosure clear; only one of the supporting columns of the 90 front brick work being shown.

Figure 2 is a perspective view illustrating the forward support for a pair of adjoining grate sections and the manner of associating and securing the same in relation to the front plate or wall of the furnace and the 105 fuel feed opening in the latter.

Figure 3 is a longitudinal sectional view showing the apparatus of Figure 1 with the hopper applied at the front of the same;

Figure 4 is a horizontal sectional view 110 looking down upon the hopper and the grate supporting means of Figure 3.

Figure 5 is a detail perspective view illustrating a modification wherein the forward or initial fuel feeding bars are of the same length as the grate bars succeeding the same 5 and also illustrating a modification of the adjoining fire brick sections for the front plate, only one of the supporting columns of the front brick work being shown.

Figure 6 is a detail vertical sectional view 10 showing the manner of forming the lower ends of the brick columns of the modification illustrated in Fig. 5.

Figure 7 is a fragmental transverse sectional view of still another modification 15 wherein separate fuel feeding openings are provided and special protecting fire brick members used to preserve the end and dividing portions of the front plate; and

Figure 8 is a vertical detail section looking 20 toward the front plate to show the fire proof protecting members of the modification disclosed in Fig. 7.

Fig. 9 is a perspective of the hopper used at the fuel opening.

Referring more specifically to the drawings wherein like reference letters designate corresponding parts in the several views, A represents the bridge wall of a furnace, B the side walls, C the front brick or arch work 30 above the fuel feed opening D in the front plate or wall E, and F represents the floor or bottom of the ash or other pit located below the grate.

At a suitable place at the rear of the fire 35 box and supported by embedding the ends thereof in the brick or other masonry walls B, I secure a horizontally arranged grate supporting bar G, the same occupying a plane substantially below the lower edge of 40 the fuel feed opening D. This bar G is formed with slots in its upper surface designated H and I, the former being of narrow width and arranged near the opposite ends of the bar G, and the latter being of double 45 width located centrally of the bar for purposes as will soon appear.

On the front plate or wall E of the furnace, I provide another grate supporting bar of a peculiarly novel formation best seen in 50 Fig. 2, the same being in the nature of a casting having a flat body or web portion J adapted to be firmly secured to the inner face of the front plate E of the furnace by suitable means, conveniently nuts and bolts 55 K. The bar under immediate consideration is preferably a casting and the web J thereof is strongly reinforced by an inwardly directed flange L resulting in an angle-bar formation at the opposite end portions of the 60 web J, the inwardly directed flange L being formed into U-shape as at M (thickened at its base m) at its middle portion to provide a recess complementary to the correspondingly located recess I in the rear bar G, it being 65 observed at this point that the front support-

ing bar is preferably located in a plane well upwardly from the plane of the rear bar G.

Inwardly extending bases or platforms N constitute integral portions of the forward bar, these base portions being in the plane 70 of the flange L and in turn surrounded by upwardly projecting inner side and end flanges n and having outer depending flanges O, the rear edges o of which abut the inner face of the front plate E to assist in 75 maintaining the forward supporting bar in place and to brace the platforms N to thereby assist the same in the supporting weight of masonry imposed thereon. Projecting outwardly from the inner lower corners of 80 the depending flanges o are somewhat Z-shaped continuations, the terminal portions P of which are adapted to be received into the brick or other masonry side walls B. previously mentioned, the other or lower 85 terminal portions p and the association thereof with the flanges O leaving recesses Q complementary to, that is of a size and aligned with, the outer slots H in the rear supporting bar G.

R indicates the outside longitudinal supports and S the inside adjoining supports for the correspondingly adjoining sets of grate and stoking members T and dumping grate members T', the supporting members R and S having end portions fitting the aligned slots and recesses H—Q, I—M, respectively. Throughout the specification and claims where I refer to adjoining sets or adjoining series of grate sections I wish it understood that I use a plurality of series of grate sections the series going forward to make up a complete grate structure and the sections of adjacent series or sets being arranged side by side. The upper inner 105 edges of the members R and S have open-topped recesses t in which pivot extensions or pintles t' rock. The dumping members T' are manipulated either alternately or together by means of depending extensions n 110 suitably linked to operating levers U. The grate and stoking members T are operated either in unison or alternately both with reference to each other and with reference to the two series of the adjoining sections by 115 means of depending extensions u' suitably connected together as the u' and linked to levers U' also in advance of the front of the furnace. Of course, it will be seen that the dumping grate sections T' are pivoted 120 reversely to the manner of pivoting the grate and stoking sections; in other words, the pivoted ends of the dumping members are arranged back to back, so to speak, with the pivots of the endmost stoking members.

In advance of the grate and stoking members T are arranged similarly pivoted fuel supporting and feed members V, the forward edges of which meet the flanges L on the front supporting bar or ledge and ex- 130

tend into the fuel receiving space immediately below the brick or other arch C. By this means the fuel is directly lifted from out of the fuel-receiving opening and fed backwardly and downwardly to the grate and stoking members inclining therefrom. The fuel feeding members V are shortened relative to the grate and stoker members T, and the pivots therefor project outwardly for a substantially longer distance than the protrusion of the pintles t so that in a sense cut-away portions provide spaces of an area coincident with the bases or platforms of fire brick portions or columns W. Of course instead of fire brick these columns like the arch C, side walls B, and bridge wall A may be of any suitable material. The fire brick columns or portions W at their inner faces are substantially flush with the ends of the fuel opening D and the said columns function to protect the face plate E beyond said opening.

On the front of the furnace wall E, I detachably suspend a feed hopper X having the supplemental pivoted false bottom or shelf Y adapted to occupy a horizontal position when loading the fuel thereupon, an inclined position when feeding the fuel through fuel opening D to the rocking feed bars V, and a vertical or upright position in closing the fuel opening when all of the fuel has been discharged from the hopper, means being provided to maintain the supplemental false bottom or support Y in its various positions of adjustment all as set forth in my said copending application Serial No. 320605. The ends of this hopper, in the instant combination, terminate near the ends of the fuel feed opening D, and in this manner spaces are left beyond the hopper and in advance of the fire brick end portions of the furnace front wall or plate within which the several grate and stoker and dumping operating handles or levers U and U' are located away from interference by the hopper in the actuating of said handles or levers and where the latter may normally occupy a position inwardly beyond the plane of the front or outer edge of the hopper. These handles or levers, of course, may be either of a permanently attached nature, or they may be of the customary detachable socketed-end type well known and readily understood in the art.

From the foregoing understanding of the improved construction therein outlined, it will be appreciated that the feeding of the fuel to the furnace will be greatly facilitated by the delivery thereof from the inclined bottom of the hopper directly on to the forward feeding members of the grate located in the fuel receiving opening below the arch C; also that the parts of the grate and stoker may be readily assembled, and grate members or side supporting bars when to be repaired easily removed; and further,—and this is quite important,—that when the parts are in assembled combination, they in operation mutually contribute to the prolongation of the life of the grate and stoker owing to the practical elimination of rigid connections such as bolts and the like securing the side supporting members to the front upper and rear lower suspending bars or ledges. In the present instance the side supporting bars are received into the aligned slots and recesses H—Q and I—M with a sufficiently close fit to secure a firm seating of the side bars and prevent lateral displacement thereof, but at the same time such fitting is relatively free to enable the side bars to contract or expand and correspondingly shorten or elongate under the variations of heat to which the fire box and related parts are subjected.

In Figure 5 I have shown that embodiment of the invention embraced in the provision of the front feeding bars 10 of full length, so to speak, that is, of the same length as the stoker bars therebeyond and to enable the use of these full length feeders while at the same time protecting the front plate of the fire box, I form the fire brick columns or protecting members, here illustrated at 11, with inclined forward lower walls 12, the inclining of these walls being to allow appropriate space for the rocking of the feed bars 10 (note Fig. 6), while enabling the lowermost edges of the fire brick protecting members to be still supported on the forward ledge as in the instance of that embodiment of the invention as herein described. There is this difference, however, namely: that in the supporting ledge of the embodiment of Figs. 5 and 6, the platforms N, as illustrated in Figure 2, for example, are dispensed with and the fire brick protecting members rest at their reduced lower edges on the end portions of the ledge L', suitable upwardly directed flanges 13 being furnished to assist in maintaining the protecting members in place and also to protect the brick against any loosening under the manipulation of furnace implements introduced through the fuel opening. These fire proof members or columns,—and this is also true of the members W of Figures 1 and 2,—may be secured in any suitable fashion either by building up and cementing in place or otherwise, but preferably the securing is of a detachable character enabling their ready removal as when access to the supporting ledge or foremost grate portions is desirable, means to this end consisting of headed bolts 14 embedded in the fire brick bodies and having protruding ends passed through suitable apertures in the front plate, and rigidly clamped thereto through the medium of the nuts 15.

Still another embodiment of the invention is disclosed in Figures 7 and 8 wherein, in lieu of a single elongated fuel feed opening,

a pair of adjoining separate openings are illustrated at 16, the supporting ledge being the same as in that form of the invention illustrated in Figures 5 and 6 and the 5 fire proof protection being also the same, with the addition of a similar intermediate detachable fireproofing member, indicated at 17, to protect the dividing portion of the front plate intermediate of the two fuel 10 openings 16. In this instance, merely cited to show the adaptability of the present invention to various types of furnaces, it is to be remembered that the idea of the front feeding hopper may be also here employed, 15 as suggested at dotted lines where separate hoppers after the fashion of the hopper of my copending case, Serial No. 320605, are indicated.

In all of the embodiments of the invention herein disclosed, it is to be observed 20 that relatively fine slits are illustrated as at 19 in the front feeding bars which will enable a small quantity of air to be supplied to the fuel at these points, but in instances 25 these slits may be dispensed with and these particular members of the grate formed solid throughout.

What I claim is:

1. In a furnace, the combination of its 30 front wall having interior grate supporting means thereon, a rear support for the grate, adjoining series of grate sections located between and operatively associated with said supports, the sections of one series being 35 arranged beside the sections of the adjoining series, the front wall of the furnace having an elongated uninterrupted fuel admission opening common to the adjoining series of grate sections and of a length 40 slightly short of the combined width of the adjoining sections, fuel feeding members whose combined length is substantially that of said opening having the forward portions thereof terminating in immediate 45 proximity to said opening to directly receive the fuel passed through said opening, and fire proof protecting columns at the ends of the fuel feeding members and between the front wall of the furnace and the immediately adjacent grate sections.

2. In a furnace, the combination of its 50 front wall having an elongated fuel admission opening, adjacent series of grate sections, the sections of one series being arranged by the side of the sections of the adjacent series and the fuel opening being common to the series of grate sections, feeding members located between said opening and the grate sections of a combined length 55 approximately that of said opening and less than the combined length of the immediately adjacent grate sections, fire proof columns located at the ends of the feeding members and between the front wall of the 60 furnace and the grate sections, and means 65

outside of the said front wall operatively associated with the grate sections to operate the same, said means being arranged laterally of said opening.

3. In a furnace, the combination of its 70 front wall having an elongated fuel admission opening, adjacent series of grate sections, the fuel opening being common to the adjacent series of grate sections and the sections of adjacent series being arranged 75 side by side, feeding means located between said opening and grate sections, said opening and feeding means being of a length short of the combined width of adjoining grate sections, fire proof protecting means 80 located at the ends of said feeding means and between said front wall and the adjacent grate sections, means outside of said front wall operatively associated with the 85 grate sections to actuate the same, said means being arranged at one side of the opening, and a front feeder associated with said opening in position so as not to interfere with the actuating means.

4. A grate supporting ledge comprising 90 a web portion adapted to be secured to the front wall of a furnace and carrying at its ends inwardly projecting supporting platforms having depending flanges at their 95 outer ends, and spaced upwardly projecting portions secured to said flanges and forming therewith upwardly opening recesses, substantially as described.

5. A grate supporting ledge comprising 100 a web portion adapted to be secured to the front wall of a furnace and carrying at its ends inwardly projecting supporting platforms having depending flanges at their outer ends, and spaced upwardly projecting 105 portions secured to said flanges and forming therewith upwardly opening recesses, said upwardly projecting portions having longitudinally offset extensions, substantially as described.

6. A grate supporting ledge comprising 110 a web portion adapted to be secured to the front wall of a furnace and carrying at its ends inwardly projecting supporting platforms, upwardly opening recessed portions located beyond said platforms and an upwardly opening recessed portion on the web portion between said platforms.

7. A grate supporting ledge comprising 115 a web portion adapted to be secured to the front wall of a furnace and carrying at its ends supporting platforms projecting inwardly in a downwardly inclined direction therefrom, the platform having upwardly directed forward flanges.

8. In a furnace including side walls, a 120 front plate having a fuel feeding opening therein, and a bridge wall, a support secured to the bridge wall, a supporting ledge secured to the front plate, said supporting ledge comprising a web portion secured to 125

130

the front plate and having adjacent its ends inwardly extending supporting platforms, a feeding grate carried by and between the support on the bridge wall and the ledge on the front plate, and a front fire wall supported on the platforms.

9. In a furnace including side walls, a front plate having a fuel feeding opening therein, and a bridge wall, a support secured 10 to the bridge wall, a supporting ledge secured to the front plate, said supporting ledge comprising a web portion secured to the front plate and having adjacent its ends inwardly extending supporting platforms 15 having upwardly extending flanges, a feeding grate carried by and between the support on the bridge wall and the ledge on the front plate, and a front fire wall supported on the platforms.

10. In a furnace including side walls, a front plate having a fuel feeding opening therein, and a bridge wall, a support secured to the bridge wall, a supporting ledge secured to the front plate, said supporting ledge comprising a web portion secured to the front plate and having adjacent its ends inwardly extending supporting platforms, each of said platforms having an upwardly extending flange on that side edge adjacent the fuel feeding opening and that end removed from the front plate, a feeding grate carried by and between the support on the bridge wall and the ledge on the front plate, and a fire wall supported on the platforms.

In testimony whereof I hereunto affix my signature.

VASIL MacKAY.
